Primary Examiner — Jack Reickel

Assistant Examiner — Bobby W Jones, II

(57) **CLAIM**

The ornamental design for a handle of gardening spray, as shown and described.

DESCRIPTION

FIG. 1 is a perspective view of a handle of gardening spray showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is another perspective schematic view of a handle of gardening spray showing my design.

The broken line showing of a handle of gardening spray is included for the purpose of illustrating portions of the article and forms no part of the claimed design.

1 Claim, 5 Drawing Sheets
